UNITED STATES PATENT OFFICE.

LEON D. BLACKMAN, OF BATTLE CREEK, MICHIGAN.

CARTRIDGE-FUSE.

1,090,445.

Specification of Letters Patent. Patented Mar. 17, 1914.

Application filed March 29, 1913. Serial No. 757,861.

To all whom it may concern:

Be it known that I, LEON D. BLACKMAN, a citizen of the United States, residing at Battle Creek, in the county of Calhoun and State of Michigan, have invented certain new and useful Improvements in Cartridge-Fuses, of which the following is a specification.

The present invention more particularly relates to refillable cartridge fuses so constructed that when one fuse is burned out another may be installed and the parts again be in readiness for use.

The main object of the invention is to construct a fuse of its class wherein the electrical contact of the assembled parts will have a large area of surface and in which the mechanical parts will be very firmly held in position and capable of being readily and easily adjusted.

It also contemplates means whereby the ferrule heads of a fuse may be changed from a round to a knife-blade style, as may be expedient.

25 It also contemplates means whereby any variation in the adjustment to render the heads of a knife-blade fuse in correlative alinement will not effect electrical contact of the assembled parts.

30 It also contemplates making the various elements of simple construction, economical to manufacture and capable of being easily assembled.

The invention with its novel features will be more fully described in connection with the accompanying drawings and will be more particularly ascertained in and by the appended claims.

In the drawings:—Figure 1 is a vertical 40 longitudinal elevation partly in section, showing the fuse with plain ferrule head. Fig. 2 is a like view showing the fuse with a knife-blade head. Fig. 3 is a plan view of the fuse-holder and its attaching cap 45 with fuse in operative position. Fig. 4 is a perspective view of the fuse-holding head. Fig. 5 is a perspective view of the fuse head. Fig. 6 is a view of the spring disk employed to compensate for the adjustment 50 in the attachment of a knife-blade head. Fig. 7 is a detail, showing the fuse passed through its holder and cap preparatory to being wound between the parts. Fig. 8 is a transverse view of the same.

55 Like marks of reference refer to corresponding parts throughout the different

views in which A represents a non-conducting cylindrical container or cartridge shell for the reception of asbestos, wool or other non-conducting filament, the same being 60 exteriorly threaded at its ends for receiving the interiorly-threaded ferrule and knife-bladed heads 1 and 2, respectively.

The manner of securing the round fuse wires 3, shown in the views is identically 65 alike; the only difference in the make-up of the fuses is a provision employed in the knife-blade style shown in Fig. 2, to aline the blades and not detract from the electrical contact of the parts, which will be herein- 70 after more fully explained.

To either end of the shell A, a fuse-holding head 4 is fitted. These heads at points about their edges have a series of stamped or otherwise provided lugs 5, which when 75 fitted extend within the shell in close engagement therewith to prevent the heads from lateral displacement. The heads further are provided with central fuse-receiving apertures 6 and oppositely-disposed perforations 7, the latter of which receive the depending lugs 8 of the caps 9.

In fitting a fuse wire 3 to the end of a shell it is inserted through the aperture 6 of a head 4 and extends somewhat beyond 85 the head; thence a cap 9 with a radially-formed open-ended slot 10 is fitted to the head with the slot striding the fuse and the lugs 8 inserted within the perforations, as shown in Figs. 7 and 8. The parts having 90 been thus far assembled, the free end of the fuse is thence bent to one side through the slot 10 in the cap 9 and passed between the cap and head 4 and wound about the lugs 8, as shown in Fig. 3.

95 Where a plain ferrule-end fuse is employed, the ferrule 1 is placed over the assembled parts and screwed onto the threaded end of the shell until the parts are firmly pressed together between the head of the ferrule and the end of the shell, as in Fig. 1.

Where a knife-blade ferrule, as 2, is employed, at least one end of the fuse is provided with a spring disk 11. This disk is fitted to the fuse between the cap 9 and the 105 knife-blade ferrule 2, as shown in Fig. 2.

To effect good resiliency the disk may be radially slotted and provided with a slightly raised center portion, as shown. The object of the disk is to afford a resilient bushing 110 between the cap and ferrule so that in screwing the ferrule on the shell perfect electrical

contact between the ferrule and cap will be effected and still make provision to coincidentally align the blades of the respective ferrules.

5. From the foregoing description it will be apparent that a fuse may be readily attached at either end of a shell and that when a fuse-wire has been burned out a new one may be easily re-fitted into position and the shell refilled without especial tools for the purpose and without undue delay in so doing.

Having, therefore, set forth the objects and advantages of my invention, what I claim as new and desire to secure by Letters

15. Patent, is:

1. In a cartridge fuse, the combination of an insulating cylindrical shell exteriorly threaded at its ends and screw-threaded ferrule members received by said ends, of head members seated on the ends of said shell and having centrally aligned apertures for the reception of a fuse and oppositely-disposed perforations, cap members having lugs fitting through said perforations and seating on said fuse when wound about said lugs, said screw ferrule members seating on said cap members.

2. In a cartridge fuse, the combination of an insulating cylindrical shell exteriorly threaded at its ends and provided with correspondingly-threaded detachable ferrule members, of head members received by said ends and provided with depending lugs to prevent lateral thrust, said head members having centrally aligned apertures for the reception of a fuse and having oppositely-disposed perforations, cap members having lugs fitted through said perforations and

seating on said fuse when wound about said lugs, said detachable ferrules seating on said cap members.

3. In a cartridge fuse, the combination of an insulating cylindrical shell exteriorly screw-threaded and provided at its ends with correspondingly-screw-threaded ferrules, of head members seated at the ends of said shell and provided with centrally aligned apertures for the reception of a fuse and having oppositely-disposed apertures, cap members having a radial open-ended slot 45 through which said fuse may be bent to clear the same, lugs depending from said caps extending through the perforations in said heads, said fuse bending about said lugs and between said cap and head at either end of 50 said shell, said screw ferrule members seated on said caps.

4. In a cartridge-fuse, the combination of an insulating cylindrical shell exteriorly threaded at its ends, of head members seated 55 at the ends of said shell and having centrally-aligned apertures for the reception of a fuse and oppositely-disposed perforations; cap members having lugs adapted to fit through said perforations and to receive the 60 bent ends of said fuse when wound thereabout between said cap and head members; a knife-blade ferrule screw-threaded onto said shell at either end thereof to effect positive electrical transmission from end to end 70 of said fuse.
